(57) **CLAIM**

The ornamental design for a gaming machine as shown and described.

DESCRIPTION

FIG. 1 is a perspective view of an embodiment of a gaming machine showing our new design;

FIG. 2 is a rear view of the gaming machine of FIG. 1;
FIG. 3 is a side view of the gaming machine of FIG. 1, an
opposite side view being a mirror image of the side view of
FIG. 3;

FIG. 4 is a top view of the gaming machine of FIG. 1;
FIG. 5 is a perspective view of another embodiment of a
gaming machine showing our new design;

FIG. 6 is a rear view of the gaming machine of FIG. 5;
FIG. 7 is a side view of the gaming machine of FIG. 5, an
opposite side view being a mirror image of the side view of
FIG. 7;

FIG. 8 is a top view of the gaming machine of FIG. 5;
FIG. 9 is a perspective view of a further embodiment of a
gaming machine showing our new design;

FIG. 10 is a rear view of the gaming machine of FIG. 9;
FIG. 11 is a side view of the gaming machine of FIG. 9, an
opposite side view being a mirror image of the side view of
FIG. 11;

FIG. 12 is a top view of the gaming machine of FIG. 9;
FIG. 13 is a frontal perspective view of a still further
embodiment of a gaming machine showing our new design;
FIG. 14 is a frontal view of the gaming machine of FIG. 13;
FIG. 15 is a rear view of the gaming machine of FIG. 13;
FIG. 16 is a side view of the gaming machine of FIG. 13, an
opposite side view being a mirror image of the side view of
FIG. 16;

FIG. 17 is a top view of the gaming machine of FIG. 13; and,
FIG. 18 is a bottom view of the gaming machine of FIG. 13.
The broken lines shown in the drawings illustrate portions of
the gaming machine that form no part of the claimed design.

1 Claim, 14 Drawing Sheets
